UNITED STATES PATENT OFFICE.

OWEN J. CARTER, OF MEMPHIS, MISSOURI.

LATCH.

1,330,168.

Specification of Letters Patent. Patented Feb. 10, 1920.

Application filed July 24, 1919. Serial No. 313,030.

To all whom it may concern:

Be it known that I, OWEN J. CARTER, a citizen of the United States, residing at Memphis, in the county of Scotland and 5 State of Missouri, have invented a new and useful Latch, of which the following is a specification.

By way of explanation it may be stated that the coöperating members of a building, 10 such as a door and a jamb, frequently shrink, leaving an opening between the door and the jamb, or elsewhere, the result being that a latch, mounted on the door, will no longer coöperate properly with a keeper mounted 15 on the jamb.

In view of the foregoing, one object of this invention is so to mount the latch, resiliently, that it may be advanced or pulled out, to co-operate with the keeper, even though the 20 door or the jamb may have shrunk, leaving an opening between the door and the jamb and separating the keeper from the latch.

A further object of the invention is to provide novel means for mounting the latch, 25 and so to construct the latch and the keeper that these parts will coact to effect a secure holding of the door or other barrier in place.

It is within the province of the disclosure to improve generally and to enhance the utility of devices of that type to which the 30 invention appertains.

With the above and other objects in view, which will appear as the description proceeds, the invention resides in the combination 35 and arrangement of parts and in the details of construction hereinafter described and claimed, it being understood that, within the scope of what is claimed, changes in the precise embodiment of the invention 40 shown can be made without departing from the spirit of the invention.

In the accompanying drawings:

Figure 1 shows in top plan, a device constructed in accordance with the invention, 45 a portion of the barrier and one jamb appearing in section; Fig. 2 is a front elevation; Fig. 3 is a section taken approximately on the line 3—3 of Fig. 2; Fig. 4 is a cross section taken approximately on the line 4—4 of Fig. 2; and Fig. 5 is a fragmental perspective showing a portion of the latch. Fig. 6 is a cross section on the line 6—6 of Fig. 2.

The numeral 1 denotes a jamb, supporting post or the like to which a barrier 2 is connected by hinges 3. The jamb with

which the free edge of the barrier 2 co-operates is denoted by the numeral 4.

In carrying out the invention there is provided a casing, denoted generally by the numeral 5, and including an arched body 6, open at the back and having a forward end wall 7, a rear wall 8, and a marginal flange 9. A plate 10 constitutes a closure for the back of the body and is overlapped upon 60 the flange 9. Securing elements 11 unite the flange 9 of the casing with the plates 10 and hold these elements on the barrier.

A slide 12 is mounted for right line reciprocity in the forward end wall 7 of 70 the casing and is supplied with a head 14 substantially filling the body portion 6 of the casing 5 transversely and slidable in engagement with the plate 10, the rear end wall 8 forming an abutment for the head 14, 75 under the action of a compression spring 15 which surrounds a portion of the slide 12, within the body 6 of the casing 5, and abuts at its ends against the forward end 7 of the casing and against the head 14 of the slide. 80 The slide 12 projects beyond the forward end wall 7 and terminates in a flattened end 18.

The numeral 16 marks a latch, having a 85 notch 17 in one end, the notch receiving the end 18 of the slide 12. The latch 16 is provided with a rearwardly extended arched projection 19 spanning the notch 17 and permitting pivotal movement of the latch with respect to the slide 12, the projection 90 abutting again the jamb 4 to form a support at the point where the end 18 of the slide 12 is connected with the latch 16 through the instrumentality of a pivot element 21 mounted on an opening 20 in the latch 16. The 95 latch 16 has a key hole slot including an opening 22 and a reduced part 23 extended from the opening toward the free end of the latch, the latch terminating in a finger piece 24 whereby the latch may be drawn endwise 100 and manipulated as occasion may demand.

The invention includes a keeper 25 having a base plate 26 and a pin projecting from the base plate, the pin having a head 27 of sufficient size to pass through the 105 opening 22 in the latch, there being a reduced neck 28 connecting the head with the base plate, the end of the pin having an opening 29, adapted to receive a lock, or seal (not shown). The base plate 26 of the keeper 25 forms a support for the intermediate portion of the latch 16, as Fig. 1

will show, and coöperates with the projection 19 on the latch 16, in affording a support for the latch.

If either the barrier 2 or the jamb 1 shrinks, so that there is an opening between these elements the part 16 may still be engaged with the keeper. The latch 16 is drawn to the right (Fig. 2), the spring 15 being compressed. The head 27 of the keeper 25 is passed through the opening 22 in the latch 16, and the latch is released, the latch moving rearwardly under the action of the spring 15, and the slide 12 moving in the end wall 7 of the casing 5. The reduced neck 28 of the pin on the keeper enters the reduced part 23 of the key hole slot in the latch 16, the head 27 extends beyond the reduced part 23 of the key hole slot, and thus the parts are held assembled, as shown in Fig. 2.

As hereinbefore stated, the latch may always be made to coöperate with the keeper even though there is a space as shown at 30 between the door 2 and the jamb 4. Further, should the door or the jamb shrink, while the latch 16 is engaged with the keeper, as shown in Fig. 2, the spring 15 will yield and the constituent parts of the device will not be torn apart, nor will the casing 5 be pulled off the door 2, or the keeper 25 be dragged off the jamb 4.

Having thus described the invention, what is claimed is:—

1. In a device of the class described, coöperating members comprising a hingedly mounted barrier and a jamb; a casing on one of said coöperating members; a slide mounted for right line reciprocation in the casing; spring means in the casing for reTRACTING the slide; a latch having a notch receiving one end of the slide, and provided with a rearwardly extended arched projection spanning the notch and permitting pivotal movement of the latch with respect to the slide, the latch having an opening; a pivot element connecting said end of the

slide with the latch, the projection abutting against the other of said coöperating elements to form a support at the point where the pivot element is located; and a keeper on said other coöperating member, the keeper comprising a base plate supporting the latch intermediate its ends, and a pin on the base plate, the pin projecting through the opening in the latch.

2. In a device of the class described, a casing comprising an arched body open at the back and having forward and rear end walls and a marginal flange; a plate constituting a closure for the back of the body and overlapped upon the flange; a securing element uniting the flange and the plate; a slide mounted to reciprocate in the forward end wall and having a head substantially filling the body transversely and slidable in engagement with the plate, the rear end wall forming an abutment for the head; a compression spring surrounding a portion of the slide and abutting against the head and against the forward end wall; a latch pivoted to the slide externally of the casing; and a keeper wherewith the latch engages.

3. In a device of the class described, a casing; a slide mounted for right line reciprocation in the casing; spring means in the casing for retracting the slide; a latch pivoted to the slide exteriorly of the casing and having a key hole slot including an opening and a reduced part extending from the opening toward the free end of the latch; and a keeper comprising a base plate, a head insertible through the opening, and a reduced neck connecting the head and the base plate and received in the reduced part of the key hole slot.

In testimony that I claim the foregoing as my own, I have hereto affixed my signature in the presence of two witnesses.

OWEN J. CARTER.
